VARIABLE POWER MAGNIFIER

Brian H. Welham, Rochester, N.Y., assignor to Bausch & Lomb Incorporated, Rochester, N.Y., a corporation of New York

Filed Sept. 1, 1960, Ser. No. 61,983

Term of patent 14 years

(Cl. D57—1)

The figure is a perspective view of a variable power magnifier showing my new design.

The side not shown is the same as the side shown.

The dominant feature of my design resides in the portions shown in full lines.

I claim:

The ornamental design for a variable power magnifier, substantially as shown and described.
